UNITED STATES PATENT OFFICE.

EDWIN KELLY, OF CAZENOVIA, WISCONSIN.

UNLOADING-PLATFORM.

1,243,948.

Specification of Letters Patent. Patented Oct. 23, 1917.

Application filed March 8, 1917. Serial No. 153,503.

To all whom it may concern:

Be it known that I, EDWIN KELLY, a citizen of the United States, residing at Cazenovia, in the county of Richland and State of Wisconsin, have invented certain new and useful Improvements in Unloading-Platforms, of which the following is a specification, reference being had to the accompanying drawings.

10 This invention relates to unloading devices and particularly to means permitting the discharge of sand, gravel, or like materials from wagons onto a platform and from thence onto a carrier whereby the sand or 15 gravel may be carried upward to a receiving bin from whence the sand or gravel may be conducted from time to time to a mixer, such as used in mixing concrete.

The general object of my invention is to 20 do away with the necessity of dumping wagons having sand or gravel upon the ground, and transporting the sand or gravel so dumped to the elevator by wheel-barrows, this being the common practice where concrete work is being done.

A further object of the invention is to 25 provide a device of this character which will permit one operator to control the conveyance of the material from the wagon to the bin or receptacle into which the sand or gravel is discharged and a further object is to provide a tilting platform coacting with 30 a carrier, the construction being such that the loaded wagons may be driven upon the platform, discharge their contents thereon, be driven off, and then the platform may be 35 tilted to discharge the gravel or sand on the platform into a carrier whereby it may be conveyed to the bin.

40 A further object of the invention is to provide a tilting platform, a carrier, and power operated means for driving the carrier and tilting the platform.

Other objects will appear in the course of 45 the following description.

My invention is illustrated in the accompanying drawings, wherein:

Figure 1 is a top plan view of my construction;

50 Fig. 2 is a section on the line 2—2 of Fig. 1;

Fig. 3 is a fragmentary elevation of the carrier 35 and the adjacent end of the platform supporting frame;

55 Fig. 4 is a fragmentary sectional view of the same parts.

Referring to these figures, 10 designates a platform, preferably made of boards mounted upon a suitable supporting frame including the beams 11 which are connected to each other and to the platform in any suitable manner.

This tilting platform 10 is mounted within a frame comprising the I-beams 12 13 14, and 15. The inner end of the platform is 60 provided with trunnions adapted to rotate in suitable bearings 17^a mounted on the beams 12, and at the outer ends of the beams 12, there are provided the uprights or standards 16 having pulleys 17 at their upper ends 65 over which pass cables 18 which extend to the free end of the platform. There are two of these cables and the cables may pass through any desired blocks, sheaves or other like arrangements of pulleys and are illustrated as each passing over a pulley 19 mounted upon the beams 12 at the base of each standard 16.

Mounted between the beams 14 and 15 at 70 one end of the space bounded by these beams is a winding drum 20. One of the cables 18 which is mounted upon the standard 16 nearest the winding drum passes directly from the pulley 19 to the winding drum, while the other cable from the cable farthest 75 from the winding drum passes parallel to the beam 13 and over a pulley 19^a and thence to the winding drum over pulleys 21. The winding drum 20 is operatively connected to a driving shaft 22 which in turn is driven by 80 any suitable motor, a clutch may be, of course, provided for connecting or disconnecting this winding drum with or from the engine shaft and means are also provided for holding the winding drum in its rotated 85 position.

Mounted upon the beams 14 and 15 are the carrier supporting rollers 23 and 24 which support the end of the carrier 25, this carrier resting upon and operating over the 90 idler rollers 26, these being mounted upon shafts 27 supported in bearings 28. The rollers 23 and 24 are also mounted on shafts 29 supported in bearings 28 and these shafts carry sprocket wheels 30 and a sprocket chain 31 passes over these sprocket wheels so that the two winding drums have driving 95 connection with each other. The shaft 29 nearest the engine is also provided with a sprocket wheel 32 over which passes a 100 sprocket chain 33 having driving engagement with a sprocket wheel 34 mounted 105

upon the engine shaft. The endless carrier 25 may be of any suitable construction and I do not wish to limit myself to any particular form for this carrier. Flash boards 5 are disposed on each side of the endless carrier so as to retain the sand or gravel thereon, it being understood, of course, that the inner edge of the platform 10 is disposed above the flash boards.

10 At the end of the platform opposite the engine is an elevator designated generally 35 which may be of any suitable construction, the elevator extending upward and discharging into a bin 36. The elevator is 15 illustrated as an ordinary endless elevator passing over a driving wheel 37 mounted on a shaft disposed below the shaft supporting the drum 24 and this shaft 38 is operatively geared to the shaft of the drum 24 20 in any suitable manner so that the power of the engine may be used to drive the elevator 35. The gravel or sand is carried into the bin 36 and from thence may be delivered as wanted into a concrete mixer of 25 any ordinary type.

Disposed at opposite ends of the platform 10 and mounted upon the beams 12 are the run-ways 39 whereby wagons may be driven up upon the platform 10 when the platform 30 is lowered and driven off from the platform 10. In actual practice, the platform 10 will be about 1' above the ground and will rest firmly in its lowered position upon the supporting frame formed of the beams 12 35 and 13.

In practical operation, the wagons will be driven upon the platform 10, the contents of the wagons will be dumped upon the platforms, and the wagons then driven 40 off. The operator then throws in the clutch which connects the winding drum 30 with the engine shaft and this causes the platform to be tilted to a certain degree so that the sand or gravel on the platform will be 45 discharged onto the endless carrier 25. This carrier is operating constantly and delivers

the sand or gravel to the elevator 35 by which it is carried into the elevated bin. It will be seen, therefore, that I have provided a very simple means for unloading wagons 50 and discharging the contents into an elevated bin which does away with the necessity of using manual labor for this purpose, and it will further be seen that the construction is simple, and may be readily transported from place to place as different jobs require. The construction is particularly designed for the use of contractors to a concrete work but it is obvious that it may be used for other purposes. It will, like- 60 wise, be obvious that while I have illustrated certain details of construction yet these details may be varied in many ways without departure from the spirit of the invention. 65

Having described the invention, what is claimed is:

An unloading device including a supporting frame having longitudinally extending parallel beams in spaced relation to 70 each other, and beams extending transversely of the first named beams, an endless carrier moving between the two parallel beams, rollers mounted between the parallel beams and supporting the endless carrier, 75 upwardly inclined sides operatively supported upon the parallel beams on each side of the carrier, brackets extending upward from the said beams to a position adjacent the edge of one of said sides, a platform pivotally mounted upon said brackets and having its inner edge extending over the carrier, and power operated means for tilting the carrier from a horizontal to an inclined position. 80

In testimony whereof I hereunto affix my signature in the presence of two witnesses.

EDWIN KELLY.
